MOSES W. LESTER, OF CHICAGO, ILLINOIS.

Letters Patent No. 94,223, dated August 31, 1869.

IMPROVEMENT IN BASE-BURNING STOVES.

The Schedule referred to in these Letters Patent and making part of the same.

To whom it may concern:

Be it known that I, MOSES W. LESTER, of Chicago, in the county of Cook, and State of Illinois, have invented a new and useful Improvement in Air-Heating Furnaces; and I do declare that the following is a true and accurate description thereof, reference being had to the accompanying drawings, and to the letters of reference marked thereon, and being a part of this specification, in which—

Figure 1 is a vertical section of my improved furnace;

Figure 2 is a horizontal section of the same, on the line *x x* in fig. 1; and

Figure 3 is the same, on the line *y y* in fig. 1.

Like letters indicate like parts in each figure.

The nature of this invention relates to an improved construction of air-heating furnaces, in which anthracite coal is used as fuel, and consists in so arranging a series of inclined air-pipes, that they will be exposed on all sides to the action of the flames; in a novel and durable form of combined combustion- and gas-rings, and in the general arrangement of its parts, as herein-after more fully shown and set forth.

In the accompanying drawings—

A, plate 1, represents the open base of my improved furnace, mounted on proper legs.

B is the ash-pit, and

C, the fire-pot.

D is an annular-flanged plate, provided with a flange, *d*, and studs *d'*, which project inwardly, and rest upon the edge of the fire-pot, leaving a small space between the flange *d* and the fire-pot, through which a sheet of air is supplied to the surface of the ignited mass of coal in the fire-pot, and thus insures a perfect combustion of the gases thrown off.

E is a combustion-ring of heavy cast-metal, forming the lower section of the magazine *F*, which is supplied with coal through the chute *f* at its top.

e are wings cast with and projecting outward from the combustion-ring *E*, and rest upon the inner edge of the gas-ring *D*.

G is a cylinder supported by a flange on the outer rim of the annular plate *D*, covered by a plate, *H*, which forms the top of the smoke-box *I*, from the centre of which plate the flue *h* rises and carries off the unconsumed products of combustion.

The diaphragm-plate *J* in the cylinder *G* forms the bottom of the smoke-box, as shown in fig. 1, and is perforated with openings, *K*, near its periphery, for the passage of the products of combustion into the smoke-box.

L are air-pipes whose lower ends fit over flanged openings near the periphery of the annular plate *D*, and passing up, incline inward and communicate with openings in the diaphragm *J*, whence the tubes *M*

convey the heated air through the smoke-box into the hot-air reservoir *O*.

P is the outer shell or casing. Its lower end is flanged into the base *A*, and its top covered by the covering-plate *Q*, which also forms the top of the air-chamber *O*, whence the heated air is conveyed to the desired points by the hot-air flues *q*.

By inclining the pipes *L*, the flame acts on all sides of them on its way to the openings *K*, and returning toward the flue *h* in the centre of the smoke-box, passes between the tubes *M*, and thus imparts the greatest possible amount of heat to the air-pipes with a given consumption of fuel. The pipes *L* being equally exposed on all sides to the action of the heat, will longer resist its destructive effects.

The combustion-ring *E* is made of heavy cast-iron, to resist the effects of the great heat to which it is subjected, and by supporting it by the wings *e* on the inner edge of the gas-ring, it may expand and contract without affecting the surrounding parts, and is easily replaced by another when necessary.

R is an evaporating-pan, conveniently placed on the ash-pit in front of the fire-pot. The evaporation of the water contained therein, supplies the requisite amount of hydrogen to the heated air issuing from the chamber *O*.

S is a tightly-fitting door, closing an opening, *s*, in the smoke-box, through which access is had to the smoke-box, for clearing away ashes on the diaphragm, plate *J*, when necessary.

If the device shown is to be used as a stove, the outer casing *P* may be made of a single thickness of sheet-metal, but if no heat is to be radiated therefrom into the apartment in which it is placed, an inner shell is added, with an air-space between them, connecting the space under the base with the reservoir *O*. Through this air-chamber the air rises and is heated, adding its quota to the air delivered by the tubes.

What I claim as my invention, and desire to secure by Letters Patent, is—

1. The inclined air-pipes *L* and tubes *M* in connection with the annular plate *D*, arranged and operating substantially as and for the purposes herein set forth.

2. The annular plate *D*, provided with flange *d* and studs *d'*, arranged and operating substantially as described.

3. In anthracite-furnaces, the combustion-ring *E*, provided with wings *e*, in combination with the annular plate *D*, when arranged and operating for the purpose set forth.

MOSES W. LESTER.
